ASSIGNORS TO MONITOR MANUFACTURING COMPANY OF BALTIMORE CITY, A
CORPORATION OF MARYLAND.

STARTER FOR ELECTRIC MOTORS.

965,649.

Specification of Letters Patent. Patented July 26, 1910.

Application filed April 9, 1907. Serial No. 367,193.

To all whom it may concern:

Be it known that we, WILLIAM C. O'BRIEN and GEORGE H. WHITTINGHAM, citizens of the United States, residing at 5 Baltimore, in the State of Maryland, have invented certain new and useful Improvements in Starters for Electric Motors, of which the following is a specification.

This invention relates to improvements in 10 automatic starters for electric motors, of the kind in which the cutting out of the starting resistance is regulated by the quantity of current flowing in the armature of circuit.

15 In the accompanying drawings, Figure 1 is a side elevation, partly in section, of a starter suitable for cutting out two steps or sections of resistance from the armature circuit, the parts being shown in their normal 20 positions: Fig. 2 is a similar view showing the starter with the line switch closed and one section of the starting resistance cut out.

25 Referring to the drawing B, C, and C' indicate solenoids mounted in a suitable metal frame *a* and arranged parallel with one another. Levers D and E are pivoted in bearings *a'* and *a''* which depend from the lower cross bar of the frame, as shown. One end of the lever D is pivoted to the core 1 of 30 the solenoid C and one end of the lever E is pivoted to the core 2 of the solenoid C'. The opposite ends of the levers extend beneath the core 3 of the solenoid B. The cores 1 and 2, as shown, are tubular so as 35 to be lighter than the core 3, which is of solid metal. The relative weights of the cores are such that when the core 3 rests upon free ends of the levers it will overbalance the combined weights of the cores 40 1 and 2 so that the latter cores will be held in their upper and most effective positions within the coils of the solenoid C and C', as shown in Fig. 1. Switch arms 4 and 5 are integrally connected to the switch levers 45 D and E respectively, so that these arms will rock with the levers into and out of engagement with stationary switch members 6 and 7, respectively.

When the parts are in their normal positions, shown in Fig. 1, the several solenoids 50 are connected in series with one another and with the entire starting resistance and with the motor armature. From terminal 8 of the line switch in Fig. 1 the circuit through

the starter extends by conductors 9 and 10 55 to the coils of the solenoid B, which may be called the holding solenoid, thence by conductors 11, 12, and 13 to the coils of the regulating solenoid C, thence through conductor 14 and one section R of the starting 60 resistance to the coils of the regulating solenoid C', thence through conductor 15 and section R' of the starting resistance to conductor 16 which leads to one brush of the motor armature *m*. From the opposite 65 brush of the motor armature the circuit extends through conductors 17 and 18 to the line switch terminal 19. The terminals of the motor field coils are, as shown, connected by conductors 20 and 21 to the conductors 9 and 18, respectively, which lead to the line switch terminals. The switch arms 4 and 5 are connected to the armature circuit by the wire 12, which, as shown is grounded 70 upon the frame of the starter. The stationary switch member is connected by a conductor 22 to an intermediate point of the coils of the solenoid C', and the stationary switch member 7 is connected by the conductor 23 to the conductor 16 which leads 75 to the armature.

The solenoids are all wound with wires of low resistance capable of carrying the full armature current. The solenoid C' has a greater length of wire in its coils than the 80 solenoid C, and, therefore, a greater attractive power over its core than has the solenoid C, with given current. When the line switch is open the parts remain as in Fig. 1, with the switches *s'* and *s''* open and 85 the resistances and the coils of all of the solenoids in series with the armature. When the line switch is closed the core of the solenoid B is drawn up into engagement with the magnet core 24, as shown in Fig. 90 2 where it remains while the motor is in operation. As soon as the current in the armature circuit falls to a predetermined quantity, by reason of the acceleration of the armature, the core of the weaker solenoid C 100 drops, and the lever D is thus rocked to close the switch *s'*, as shown in Fig. 2. The solenoid C and resistance section R, and a part of the windings of solenoid C' are thereby short circuited, the armature current 105 then passing from the line terminal around the coils of solenoid B to conductor 11 and the frame of the starter, thence

through switch arm 4 and contact 6 to the conductor 22, thence through part of the windings of the solenoids C' to resistance section R', and thence through conductors 13 and 16 to the motor armature and to the line terminal 19 by way of conductor 18.

The conductor 22 leading from the switch contact 6 is connected to the coil of solenoid C' at a point which will cause a sufficient length of wire on the solenoid to be short circuited, when the switch s' closes, to weaken the solenoid so that its core will drop when the current decreases to a point where it is desirable and safe to cut out the remaining section of the resistance. The downward movement of the core of the solenoid C' rocks the lever E and closes the switch s². A shunt is thus formed around the coils of solenoid C' and the resistance section R'. The armature current then flows from the conductor 11 through switch arm 5, contact 7 and conductors 23 and 16 to the armature, instead of through the solenoid coils and resistance. When the line switch is opened the coils of solenoid B being thus deenergized, the core of said solenoid drops onto the adjacent ends of the levers D and E and rocks the levers to open the switches s' and s², thus reinserting the resistance sections and the coils of solenoids C and C' in the armature circuit and moving the cores of said solenoids to their upper positions.

It is not necessary to have the solenoid B, in the above described starter, connected in series with the armature, as this solenoid may be connected in any suitable way so as to be energized when the current is turned on at the line switch; but it is preferably arranged in series, as shown.

Various forms of magnets with movable cores or armatures may obviously be used to carry out the invention, although the solenoid form is preferred. For convenience, the devices which regulate the closing of the switches according to the quantity of current flowing in the armature circuit will be referred to in the claims as the regulating solenoids or devices, and the device which controls the movement of the switches to open position when current is cut off will be referred to as the holding solenoid or device.

We claim,—

1. In an automatic starter for electric motors, a starting resistance in the armature circuit, two regulating solenoids having their windings in said circuit, one of said solenoids being wound so that its core will be released when the current in the armature circuit falls below a predetermined quantity, and the other being wound to support its core with less than the said quantity of current flowing, a circuit for shunting the coils of the weaker solenoid and a section of the starting resistance and a

portion of the windings of the stronger solenoid, a switch in said shunt circuit adapted to be closed by the movement of the core of said weaker solenoid when released from its coils, a circuit for shunting the remaining coils of said stronger solenoid and a section of the starting resistance, a switch in said latter circuit adapted to be closed by the movement of the core of said stronger solenoid when released from its coils, levers engaging the cores of said regulating solenoids, and a holding solenoid having a core adapted to normally bear upon said levers and overbalance the cores of said regulating solenoids, thereby holding the switches normally in open positions.

2. In an automatic starter for electric motors, a starting resistance in the armature circuit, two regulating solenoids having their windings in said circuit, one of said solenoids being wound so that its core will be released when the current in the armature circuit falls below a predetermined quantity, and the other being wound to support its core with less than the said quantity of current flowing, a circuit for shunting the coils of the weaker solenoid and a section of the starting resistance and a portion of the windings of the stronger solenoid, a switch in said shunt circuit adapted to be closed by the movement of the core of said weaker solenoid when released from its coils, a circuit for shunting the remaining coils of said stronger solenoid and a section of the starting resistance, a switch in said latter circuit adapted to be closed by the movement of the core of said stronger solenoid when released from its coils, levers engaging the cores of said regulating solenoids, and a holding solenoid having a core adapted to normally bear upon said levers and overbalance the cores of said regulating solenoids, thereby holding the switches normally in open positions.

3. An automatic starter for electric motors comprising a starting resistance in the armature circuit, two electro-magnetic regulating devices having their windings in said circuit, one of said devices being arranged so that its core or armature will be released when the current in the armature circuit falls below a predetermined quantity, and the other being wound to support its core or armature with less than the said quantity of current flowing, a circuit for shunting the coils of the weaker device and a section of the starting resistance and a portion of the windings of the stronger device, a switch in said shunt circuit adapted to be closed by the movement of the core or armature of said weaker device when released from its coils, a circuit for shunting the remaining coils of said stronger device and a section of the starting resistance, a switch

in said latter circuit adapted to be closed by the movement of the core or armature of said stronger device when released from its coils, levers engaging the cores or armatures of said regulating devices, and a holding device having a core or armature adapted to normally bear upon said levers and overbalance the cores or armatures of said regulating devices, thereby holding the 10 switches normally in open positions.

4. An automatic starter for electric motors comprising a starting resistance in the armature circuit, two electro-magnetic regulating devices having their windings in said 15 circuit, one of said devices being arranged so that its core or armature will be released when the current in the armature circuit falls below a predetermined quantity, and the other being wound to support its core or 20 armature with less than the said quantity of current flowing, a circuit for shunting the coils of the weaker device and a section of the starting resistance and a portion of the windings of the stronger device, a switch in

said shunt circuit adapted to be closed by 25 the movement of the core or armature of said weaker device when released from its coils, a circuit for shunting the remaining coils of said stronger device and a section of the starting resistance, a switch in said latter circuit adapted to be closed by the movement of the core or armature of said stronger device when released from its coils, levers engaging the cores or armatures of said regulating device, and a holding device having windings in the armature circuit and having a core or armature adapted to normally bear upon said levers and overbalance the cores or armatures of said regulating devices, thereby holding the switches 30 35 normally in open position.

In testimony whereof we affix our signatures, in presence of two witnesses.
